CONTROL FOR OPERATING ELEVATOR SYSTEMS

Harold C. Crane, Toronto, Ontario, Canada

Application May 6, 1952, Serial No. 286,227

22 Claims. (Cl. 187—29)

1

This invention relates to a control for an elevator system serving a plurality of floors of a building.

In known elevator systems, during periods of heavy traffic such as the evening departure traffic peak, service is apt to be slow. Various controls have been devised to improve service during these periods. For example, some controls measure the time from which a signal is made, and if a predetermined time elapses and the signal remains unanswered that signal is answered in priority to others which were subsequently made. Other controls assign a zone of floors and a quota of signals to each car. In the known systems, however, service may be slow due to the fact that each car of the elevator system makes a large number of stops, frequently picking up only one passenger at a stop.

It is an object of the invention to improve service in an elevator system when signals for a car are made from several floors.

It is another object of the invention to reduce the number of stops made by a car of an elevator system and to increase the average number of passengers picked up at each stop.

In the embodiment of the invention herein-after described in greater detail, the car stopping means of an elevator system are operated in the sequence in which signals are made from the various floors, but when a predetermined number of car stopping means is in operation, the operation of further car stopping means is delayed until the number of car stopping means in operation falls below the predetermined number; a car stopping means is rendered inoperative when a car is stopped at its associated floor. Thus, only a predetermined number of car stopping means is in operation at one time, and the car stopping means that are in operation are those for the floors from which the earliest signals were made. Later signals are held in abeyance on signal registers which are coupled together to register the signals in the order in which they are made, and the signal registers operate the car stopping means for their associated floors only as prior operated car stopping means are rendered inoperative. Since only a predetermined number of car stopping means is in operation at one time, the number of stops made by a car can be held to, say, two or three for each trip in a given direction, and since the earliest made signals are answered first the number of passengers picked up at each stop is greater on the average than in systems having conventional controls. In modern elevator systems, it takes about six seconds for deceleration,

2

door time, and subsequent acceleration, so that if three or four stops are eliminated the round trip time is reduced by 20 to 25 seconds, or by, say, 25%. Furthermore, since in accordance with this invention the number of car stopping means in operation at a given time is reduced, a car will, on the average, reverse at a lower floor than it does when all the car stopping means for which signals have been made are in operation at the same time. In the result, since a car makes more trips per hour the system can handle a higher peak rate of traffic, or can handle the same traffic with the average number of passengers in a car reduced about 35%.

15 Also in the embodiment hereinafter described, a plurality of floors of a building are provided with signal registers responsive to signals from the signalling means for their associated floors to register the signals, and the signal registers 20 are coupled together to register the signals in a predetermined sequence and to operate the car stopping means for their associated floors in a predetermined sequence, but only a predetermined number of car stopping means can be operated at one time. For registering the signals each signal register preferably has an arm movable to a plurality of positions, and the means coupling the signal registers together controls the positions of the arms, thus controlling the sequence in which the signals are recorded on the registers and controlling the sequence in which the car stopping means are operated.

25 A further feature of the invention is the provision of means operable to reverse an ascending car in response to the time of ascent of a car and/or in response to the number of signals that have been made from the signalling means. A still further feature is the provision of means responsive to the number of signals made to vary the interval between cars.

30 The single figure of the drawings illustrates one embodiment of the invention. The embodiment illustrated employs a stepping switch for each floor above the ground floor of the building, each stepping switch constituting a signal register. For the purpose of this description it will be assumed that the building has ten floors above the ground floor, but for simplicity the connections for only a single upper floor are shown, the 35 connections for the other upper floors being similar. Additional connections common to all floors are also shown. Connections for only the "down" button are shown, since normally it is not necessary to give priority to "up" signals at the various floors.

The stepping switch for each upper floor is of conventional construction and is illustrated diagrammatically. The switch has four groups of contacts, known in the stepping switch art as "levels," designated in the drawings as level A, level B, level C and level D. Each level has a "dummy" contact, hereinafter called the normal contact, and, for a building having ten upper floors, each level has ten additional contacts. The additional contacts for level A are designated A₁, A₂ . . . A₁₀, those for level B are designated B₁, B₂ . . . B₁₀, and so on. The normal contacts are designated AN, BN, CN and DN. For each level, the stepping switch has a wiper, the wipers being designated WA for level A, WB for level B, WC for level C, and WD for level D. The wipers are mounted for synchronous rotation (counterclockwise, as illustrated) on a common shaft 12, and each wiper has three arms 120° apart. In the drawings, the wipers are shown in what will be called the normal position, which is taken up when no down signal is registered for the associated floor; in this position, an arm of each wiper rests on a normal contact. If a wiper is rotated 120°, the arm which formerly rested on the normal contact moves over all the contacts of its level, coming to rest beyond the first contact, and another arm of the wiper comes to rest on the normal contact. As will be seen below, if the first down signal in the building is made at, say, the fifth floor, the stepping switch for the fifth floor moves to what will be called the "first position," with an arm of wiper WA at contact A₁, an arm of wiper WB at contact B₁, and so on. If the down signal for the fifth floor remains unanswered, and a down signal is next made at the seventh floor, the stepping switch for the seventh floor moves to the "second position," with an arm of its wiper WA at its contact A₂, an arm of its wiper WB at its contact B₂, and so on. Similarly if unanswered down signals are made at all ten floors, the stepping switch for the floor at which a down signal was last made takes up the "tenth position" with its wipers on its contacts A₁₀, B₁₀, C₁₀ and D₁₀. Thus, the order in which the signals are made at the various floors is reflected in the positions taken by the stepping switches associated with the floors to register the signals, and suitable connections are made at each position to give the first registered signals the highest priority. Only the two (for example) longest registered signals are passed on to car stopping means which stop the next cars at the floors from which the signals came, and the remainder of the signals are held in suspense in the order in which they were registered. As soon as the signal for one floor is answered, the stepping switch for that floor returns to the normal position to await a further down signal, and the stepping switches which had occupied higher numbered positions move one step to lower numbered positions. Thus, if X signals are waiting to be answered, the stepping switch for the floor for which the last signal was registered always occupies the X position.

Each stepping switch has motive mechanism consisting of a solenoid 13 connected in series with a normally closed interrupter contact 14. According to conventional stepping switch operation, if voltage is supplied across the solenoid 13 and the contact 14, the solenoid is energized and opens the contact 14. With the contact 14 open, the solenoid is de-energized and the con-

tact 14 re-closes. On the re-closing of the contact 14, a ratchet (not shown) rotates the wipers counterclockwise one step to the next position. If voltage is still being supplied across the solenoid 13 and the contact 14, the operation repeats and the switch takes another step.

The solenoid 13 and contact 14 are connected between a negative supply line 15 and a single pole double throw switch 16. The switch 16 is operated by a cam 17 mounted on the shaft 12, and the cam is rotatable synchronously with the wipers WA, WB, WC and WD. When the wipers are in the normal position, the cam 17 holds the switch 16 in what will be called its normal position, in which it is connected through the down button 18 at the associated floor to a positive supply line 19. When the down button 18 is pressed, the solenoid 13 is energized and the stepping switch takes a step, moving the wipers to the tenth position contacts A₁₀, B₁₀, C₁₀ and D₁₀ and rotating the cam 17, permitting the switch 16 to move to its other position, where a normally open reset contact 20 breaks the circuit from the line 19 via the switch 16 to the solenoid 13.

Let it be assumed that the down button at only the fifth floor has been pressed, so that the stepping switches for all other floors are in the normal position. As described in the preceding paragraph, in response to a signal from the down button at the fifth floor, the stepping switch for the fifth floor moves to the tenth position. The contacts A₂ to A₁₀ are connected to the positive line 19 through connections AA and through normally closed relay contacts R₁ to R₉ respectively. The connections AA connect the contacts A₂ to A₁₀ for each upper floor to the contacts A₂ to A₁₀ respectively for every other upper floor so that the A contacts for all upper floors are in the same condition of energization or de-energization. The wiper WA is permanently connected by a lead 21 to the interrupter contact 14, on the same side of the contact 14 as the switch 16. When the wiper WA is on the contact A₁₀, a circuit is completed from the positive line 19 through the relay contact R₉, the contact A₁₀, the wiper WA, the lead 21, the contact 14 and the solenoid 13 to the negative line 15. Thus, the stepping switch moves another step to the ninth position. At the ninth position, since the relay contact R₈ is closed, the switch takes another step to the eighth position, and so on until it reaches the first position. The contact A₁ is not connected to the line 19, so that at this position voltage is no longer supplied to the solenoid 13 and the stepping switch remains in the first position.

The wiper WB is permanently connected by a lead 22 to the line 15. The contacts B₁ to B₉ are connected to the line 19 through connections BB and through the coils of blocking relays R₁ to R₉ respectively which control the contacts R₁ to R₉. The connections BB connect the contacts B₁ to B₉ of each stepping switch to the contacts B₁ to B₉ respectively of the stepping switches for all other floors. With the stepping switch for the fifth floor in the first position, a circuit is completed from the line 19 through the coil of blocking relay R₁ to the contact B₁ for the fifth floor, and thence through the wiper WB for the fifth floor and the lead 22 to the line 15. The relay R₁ is thereby energized and opens the contact R₁, thus disconnecting the contacts A₂ for every floor from the line 19. If the next down button pushed is on,

say, the seventh floor, the stepping switch for the seventh floor will proceed only as far as the second position, since the contacts **A2** for every floor are not energized. The wiper **WB** for the seventh floor takes up the second position, on contact **B2**, energizing the blocking relay **R2** and opening the relay contact **R2**, thus de-energizing the contacts **A3** so that the next stepping switch to be operated by pressing a down button will stop at the third position, and so on. In general, if any position **X** is occupied by a stepping switch, the next stepping switch to operate in response to a signal from the down button for its associated floor will take up the position **X+1**, so that the signals from the various floors are registered in the sequence in which they are made. The positions to which the wipers move are controlled by the blocking relays which are common to all the stepping switches and thus couple them together. As will now be described with reference to level **C**, the blocking relays, by preventing successively operated stepping switches from overtaking one another, limit the number of car stopping means in operation at one time to a predetermined number, so that the earliest signals to be registered are answered first and the answering of subsequent signals is delayed.

The wiper **WC** is permanently connected through a resistor **23** and a relay **24** to the line **15**. The relay **24** is a conventional floor relay which, when energized, causes the next descending car to stop at the floor with which the relay is associated. The contacts **C1** and **C2** are permanently connected to the line **19** through a connection **CC** and a lead **25**, so that when the wiper **WC** is in either the first or the second position the floor relay **24** is energized. The contacts **C4** to **C10** inclusive are connected together by means of a shunt **27**, and the shunt **27** is connected to the line **19** through a connection **CC** and a normally closed relay contact **RC**. The contact **C3** is connected through a connection **CC** to a single pole double throw switch **28** which, in one position, connects the contact **C3** through the lead **25** to the line **19**, and in its other position connects the contact **C3** through the relay contact **RC** to the line **19**. The connections **CC** link together the corresponding **C** contacts of all the stepping switches.

The relay contact **RC** opens as soon as the first and second positions are occupied. This is achieved by connecting a call relay **RC** in series with two normally open relay contacts **R1a** and **R2a** across the lines **15** and **19**. The relay contacts **R1a** and **R2a** close when the blocking relays **R1** and **R2** are energized, and these are energized when the first and second positions are occupied at the levels **B**. When the relay contacts **R1a** and **R2a** are closed, the call relay **RC** is energized, and this relay opens the relay contact **RC**. A condenser **29** is connected in parallel with the call relay **RC** to slow down the drop-out of the relay.

Assume for the moment that the contacts **C3** of the stepping switches are connected by the switch **28** to the relay contact **RC**. With the first and second positions of the stepping switches occupied, and the relay contact **RC** open, when a third signal comes in, say on the ninth floor, the ninth floor stepping switch moves to the third position, but since the contacts **C3** are not connected to the line **19** the floor relay for the ninth floor does not become energized. Similarly, subsequent signals are

held in suspense at the fourth, fifth, etc. positions.

The purpose of the relay **RC** is to maintain service if one of the stepping switches sticks. If one of the stepping switches sticks, it prevents any subsequently operating stepping switch from overtaking it, and therefore there will be unoccupied high priority positions. The relay **RC** ensures that if the first two positions are not occupied, the floor relays will be picked up by stepping switches occupying higher numbered positions so that all car stopping means for which signals have been made are operated concurrently until the first two positions are taken up. Priority is thereby lost, but at least service is maintained.

Let it be assumed that the down buttons have been pressed at the fifth, seventh, ninth and second floors, in that order, so that the stepping switches for these floors occupy the first, second, third and fourth positions, respectively. Further let it be assumed that the switch **28** is connected to the contact **RC**, which of course will be open. With the switch **28** connected to the contact **RC**, the only floor relays **24** that are energized are those for the fifth and seventh floors. A descending car will be stopped, first, at the seventh floor. When the car stops at the seventh floor it closes the reset contact **20** for the seventh floor so that the seventh floor solenoid **13** is energized through the switch **16** and the seventh floor stepping switch moves counterclockwise to the normal position; at the normal position, the cam **17** returns the switch **16** to the position shown in the drawings, thus stopping the stepping switch until the seventh floor down button **18** is pressed again. By returning the seventh floor stepping switch to its normal position, the reset contact **20** uncouples the seventh floor relay **24** from the stepping switch and renders that floor relay inoperative.

Due to the movement of the wiper **WB** of the seventh floor stepping switch from the second position, the relay **R2** is de-energized, and the ninth and second floor stepping switches can move to the second and third positions, respectively. Meanwhile, the car descends to the fifth floor. Thus, only the first two or three signals are answered by the first descending car; the number of signals given highest priority can be varied by changing the position of the switch **28**. Further, it will be seen that as the earliest operated stepping switches are returned to their normal positions, subsequently operated stepping switches advance, in the sequence in which signals were registered on them, to the positions where they are coupled to the floor relays for their associated floors.

The contacts **D1** and **D2** are connected to the line **19** through a connection **DD** and a flasher **29**. The contacts **D4** to **D10** inclusive are connected to a shunt **30**, and the shunt **30** is connected to the line **19** through a connection **DD** and a lead **31**. The contact **D3** is connected through a connection **DD** to a single pole double throw switch **32** which can be connected either to the flasher **29** or the lead **31**. The wiper **WD** is connected to the line **15** through a signal indicator light **33** at the ground floor. Thus, for the stepping switches which are at the highest priority positions, the signal indicator lights for the associated floors give a flashing indication because they are connected through the flasher **29**, whereas the signal indicator lights for lower priority signals operate without flashing because they are connected di-

rectly to the line 18 through the lead 31. The signal indicator lights 33 are arranged on an indicator panel on the ground floor, where they inform the starter and the public as to which signals have the highest priority.

As in most elevator systems, a manual switch 34 is provided on the starter's control panel on the ground floor, and this switch is connected in series with a "high call reversal" relay 35 across the lines 15 and 19. When the relay 35 is energized, it reverses each ascending car at the floor for which the highest signal has been made, whether the signal was made by means of a hall button or by means of a button in the car. The starter may close the switch 34 during those periods of the day when the cars are most in demand, so that the cars need not travel to the top floor before reversing.

According to this invention, means are provided to cut the high call reversal relay in and out automatically as traffic conditions vary. A normally open relay contact R2b is connected across the switch 34; the contact R2b closes when the blocking relay R2 is energized, thus causing the high call reversal relay 35 to pick up as soon as two down signals are registered. Also connected across the switch 34 is a circuit consisting of normally open relay contact R1b in series with a bank of normally open timing relay contacts T1, T2 and T3, the latter contacts being connected in parallel. The contact R1b closes when the blocking relay R2 is energized, i. e. when one down signal is registered. Each timing relay contact is controlled by a timing relay (not shown) associated with one of the cars; it is here assumed that there are three cars and therefore three timing relays. Each timing relay is set to close its timing relay contact if the associated car is still travelling up after, say, 40 seconds from the time it left the ground floor. Thus, if there is one down signal registered, and any car takes more than 40 seconds on the up trip, the high call reversal relay 35 is energized. Also connected across the switch 34 is a bank of normally open timing relay contacts TT1, TT2 and TT3, connected in parallel. These contacts are closed by another group of timing relays (not shown) set to operate if any car is still travelling up after, say, 50 seconds from the time it left the ground floor. These last relays are useful during the morning rush hour when all the traffic is in the up direction.

In many elevator systems, a variable speed timer motor is provided to maintain a desired interval between the times that successive cars leave the ground floor. A potentiometer is provided by means of which the starter can vary the speed of the timer motor, thus varying the interval between cars.

According to this invention, the time interval between cars may be automatically varied to prevent waste of time at the ground floor during periods of heavy down traffic. Connected across the lines 15 and 19 is a potentiometer 36 and the shunt field winding 37 of a direct current timer motor 38. One side of the armature of the motor 38 is connected to the line 15, and the other side is connected to a network 39. Depending upon down traffic conditions, the network connects the armature to different points on the potentiometer 36, thus varying the voltage supplied to the armature of the motor whereby the motor varies the time interval between cars. The network 39 consists of a pair of normally open contacts R2c and

5 R3c connected in series between the armature of the motor and the line 15, a normally closed contact R2d connected to the armature and to a variable tap 36a on the potentiometer 36, and a normally closed contact R3d connected to a point between the contacts R2c and R3c and to a variable tap 36b on the potentiometer. The contacts R2c and R3c close when the second and third positions respectively are occupied by stepping switches, and the contacts R2d and R3d open when the second and third positions respectively are occupied by stepping switches. Thus, when no down signals are registered, or when only one down signal is registered, the armature of the motor 38 is connected through the contact R2d to the tap 36a, a relatively low voltage is applied to the armature, and the motor rotates at a speed corresponding to the desired time interval between cars for this traffic condition. The position of the tap 36a can of course be varied as desired.

10 When two down signals are registered, the contact R2d opens and the contact R2c closes, connecting the armature to the tap 36b, thus supplying a higher voltage to the armature and speeding up the motor to reduce the time interval between cars. Similarly, when three down signals are registered, the contact R3d opens and the contact R3c closes, giving full voltage to the armature and a minimum time interval between cars.

20 For convenience in servicing and for economy in wiring, most of the apparatus that has been described is located in the penthouse of the building: each upper floor merely has a push-button 18, and the indicating lights 33 and the switch 34 are at the ground floor.

25 The invention has been described as applied to an elevator system having floor relays 24, but it will be obvious to those skilled in the art that the floor relays may be eliminated and the stopping of the cars may be controlled directly by the stepping switches. The form of the invention herewith shown and described is merely a preferred example, and many changes in apparatus and arrangement may be made without departing from the scope of the invention as defined in the subjoined claims.

30 What I claim as my invention is:

35 1. A control for an elevator system serving a plurality of upper floors of a building, comprising car stopping means associated with each said floor and operable to stop a car of the elevator system at the associated floor, the car stopping means being rendered inoperative upon stopping a car, signalling means for each said floor from which a signal may be made when it is desired to operate the car stopping means associated with that floor, signal registering means responsive to signals made from the signalling means to register the signals in the sequence in which they are made, the signal registering means operating the car stopping means for which signals have been made in the sequence in which the signals are registered, and blocking means for delaying the operation of further car stopping means until the number of car stopping means already in operation falls below a predetermined number.

40 2. A control for an elevator system serving a plurality of upper floors of a building, comprising car stopping means associated with each said floor and operable to stop a car of the elevator system at the associated floor, the car stopping means being rendered inoperative upon stopping a car, signalling means for each said floor from which a signal may be made when it is desired

to operate the car stopping means associated with that floor, signal registering means responsive to signals made from the signalling means to register the signals in the sequence in which they are made, the signal registering means operating the car stopping means for which signals have been made in the sequence in which the signals are registered, the signal registering means including means for operating concurrently all car stopping means for which signals are made until the number of car stopping means in operation reaches a predetermined number, and blocking means for delaying the operation by the signal registering means of further car stopping means until the number of car stopping means already in operation falls below the predetermined number.

3. A control for an elevator system serving a plurality of upper floors of a building, comprising car stopping means associated with each said floor and operable to stop a car of the elevator system at the associated floor, the car stopping means being rendered inoperative upon stopping a car, signalling means for each said floor from which a signal may be made when it is desired to operate the car stopping means associated with that floor, a signal register associated with each said floor and interposed between the signalling means for that floor and the car stopping means for that floor, the signal registers being responsive to signals made from the signalling means for the floors with which the signal registers are associated to register the signals, the signal registers being coupled together to register the signals in the sequence in which they are made, and the signal registers operating the car stopping means for the floors with which the signal registers are associated as prior operated car stopping means are rendered inoperative, the signal registers operating the car stopping means in the sequence in which the signals are registered.

4. A control for an elevator system serving a plurality of upper floors of a building, comprising car stopping means associated with each said floor and operable to stop a car of the elevator system at the associated floor, signalling means for each said floor from which a signal may be made when it is desired to operate the car stopping means associated with that floor, a signal register for each said floor interposed between the signalling means for that floor and the car stopping means for that floor, each signal register being responsive to a signal from the signalling means for its floor to register the said signal, the signal registers being coupled together to register the signals in the sequence in which the signals are made, the signal registers operating the car stopping means for their floors in the sequence in which the signals are registered, and means blocking operation of the car stopping means to limit the number of car stopping means in operation at any time to a predetermined number.

5. A control for an elevator system serving a plurality of upper floors of a building, comprising car stopping means associated with each said floor and operable to stop a car of the elevator system at the associated floor, the car stopping means being rendered inoperative upon stopping a car, signalling means for each said floor from which a signal may be made when it is desired to operate the car stopping means associated with that floor, a signal register for each said floor responsive to a signal from the signalling means for that floor to register the said signal, the sig-

nal registers being coupled together to register the signals in the sequence in which the signals are made, the signal registers operating the car stopping means in the sequence in which the signals are registered and having means associated with the signal registers for blocking operation of further car stopping means when a predetermined number of car stopping means is in operation, the blocking means permitting operation of further car stopping means as prior operated car stopping means are rendered inoperative.

6. A control for an elevator system serving a plurality of upper floors of a building, comprising car stopping means associated with each said floor and operable to stop a car of the elevator system at the associated floor, signalling means for each floor from which a signal may be made when it is desired to operate the car stopping means associated with that floor, a signal register associated with each said floor and responsive to a signal from the signalling means for the associated floor to register the said signal, means for coupling a predetermined number of signal registers to the car stopping means for their associated floors, the predetermined number of signal registers operating the car stopping means to which they are coupled, means for uncoupling the signal registers up to the predetermined number may be coupled to the car stopping means for their associated floors, and means coupling the signal registers together for controlling the sequence in which the signal registers are coupled to the car stopping means.

7. A control for an elevator system serving a plurality of upper floors of a building, comprising car stopping means associated with each said floor and operable to stop a car of the elevator system at the associated floor, signalling means for each said floor from which a signal may be made when it is desired to operate the car stopping means associated with that floor, a signal register associated with each said floor and having an arm movable in response to a signal from the signalling means for the associated floor to register said signal, means for coupling a predetermined number of signal registers to the car stopping means for their associated floors, the predetermined number of signal registers operating the car stopping means to which they are coupled, means for uncoupling the signal registers from the car stopping means as cars are stopped at the associated floors so that further signal registers up to the predetermined number may be coupled to the car stopping means for their associated floors and means coupling the signal registers together and responsive to movement of the arms for controlling the sequence in which the signal registers are coupled to the car stopping means.

8. A control for an elevator system serving a plurality of upper floors of a building, comprising car stopping means associated with each said floor and operable to stop a car of the elevator system at the associated floor, signalling means for each said floor from which a signal may be made when it is desired to operate the car stopping means associated with that floor, a signal register associated with each said floor operable in response to a signal from the signalling means for the associated floor and having an arm movable to a plurality of positions, the arm being movable to one of said positions in response to said signal to register said signal, means coupling the signal registers together, the coupling means

controlling the positions to which the arms of successively operated signal registers move in response to signals from the signalling means for their associated floor whereby the signals are registered in a predetermined sequence, and means for coupling signal registers to the car stopping means for their associated floors, the signal registers operating the car stopping means in the predetermined sequence.

9. A control for an elevator system serving a plurality of upper floors of a building, comprising car stopping means associated with each said floor and operable to stop a car of the elevator system at the associated floor, signalling means for each said floor from which a signal may be made when it is desired to operate the car stopping means associated with that floor, a signal register associated with each said floor operable in response to a signal from the signalling means for the associated floor and having an arm movable to a plurality of positions, which positions correspond to similar positions of the other signal registers, the arm of each register being movable to one of its positions in response to said signal from the signalling means for the associated floor to register said signal, means coupling the signal registers together, the coupling means controlling the positions to which the arms of successively operated signal registers move whereby the earliest operated signal registers take up predetermined positions, means for coupling the signal registers taking up the predetermined positions to the car stopping means for their associated floors in priority to other signal registers, and means for operating concurrently all car stopping means for which signals are made until said predetermined positions are all taken up.

10. A control for an elevator system serving a plurality of upper floors of a building, comprising car stopping means associated with each said floor and operable to stop a car of the elevator system at the associated floor, signalling means for each said floor from which a signal may be made when it is desired to stop a car at that floor, a signal register for each said floor operable in response to a signal from the signalling means for the associated floor, each signal register having an arm movable to a plurality of numbered positions in succession, which positions correspond to similarly numbered positions of the other signal registers, the arm being movable to one of its positions in response to said signal from the signalling means for the associated floor to register said signal, means coupling the signal registers together, the coupling means controlling the movement of the arms of successively operated signal registers whereby the arms take up consecutive numbered positions to register the signals in a predetermined sequence, the signal registers operating the car stopping means for their associated floors in the sequence in which the signals are registered, and the coupling means including means blocking operation of the car stopping means to limit the number of car stopping means in operation at any time to a predetermined number.

11. A control for an elevator system serving a plurality of upper floors of a building, comprising car stopping means associated with each said floor and operable to stop a car of the elevator system at the associated floor, signalling means for each said floor from which a signal may be made when it is desired to stop a car at that floor, a stepping switch associated with each said

floor and operable in response to a signal from the signalling means for the associated floor, each stepping switch having stepping means movable from a normal position to a plurality of numbered positions in succession, the numbered positions of each stepping switch corresponding to similarly numbered positions of the other stepping switches, the stepping means being movable to one of the numbered positions in response to said signal from the signalling means for the associated floor to register said signal, means coupling the stepping switches together, the coupling means including blocking means associated with the numbered positions and actuated by the stepping means of a switch occupying a numbered position to prevent the stepping means of the next operated stepping switch from moving to that position until the position is unoccupied, whereby the stepping means of the stepping switches take up consecutive numbered positions in the order in which they are operated, means for coupling a predetermined number of stepping switches whose stepping means occupy predetermined numbered positions to the car stopping means for their associated floors, the predetermined number of stepping switches operating the car stopping means to which they are coupled, means for returning the stepping means of each of the predetermined number of stepping switches from the predetermined position occupied by the stepping switch to its normal position when a car is stopped at the associated floor whereby the stepping switch is uncoupled from the associated car stopping means, thus rendering inoperative the car stopping means and the blocking means associated with the predetermined position so that the stepping means of another stepping switch can move to the predetermined position.

12. A control for an elevator system serving a plurality of upper floors of a building, comprising car stopping means associated with each said floor and operable to stop a car of the elevator system at the associated floor, signalling means for each said floor from which an electrical signal may be made when it is desired to stop a car at that floor, a source of electrical energy, a stepping switch associated with each said floor, each stepping switch having electrically operable motive mechanism and a pair of arms movable by the motive mechanism in synchronism, each arm having a plurality of positions, the positions of one arm comprising, in sequence, a normal position, a plurality of contacts normally energized from the source of electrical energy, said contacts forming normally energized positions of the one arm, and a non-energized position of the one arm, and the positions of the other arm comprising, in sequence, a normal position and a plurality of subsequent positions to which said other arm is movable in synchronism with said one arm, the positions of each stepping switch corresponding to similar positions of the other stepping switches, the motive mechanism of each stepping switch being actuated by an electrical signal from the signalling means for the associated floor to move the one arm of the stepping switch from its normal position to a normally energized position, the contact of said position when energized connecting the one arm and the motive mechanism in series with the source of electrical energy whereby the motive mechanism is actuated to move the one arm to the next normally energized position, and so on until the

one arm reaches a non-energized position at which the motive mechanism is not actuated, the one arm taking up said non-energized position, and the other arm, having moved in synchronism with said one arm, taking up one of its subsequent positions, means coupling the stepping switches together, the coupling means including blocking means actuated by said other arm at said subsequent position to de-energize for all the stepping switches the contact of the normally energized position prior to the position taken up by said one arm whereby said prior position becomes the non-energized position taken up by the next operated stepping switch, so that the subsequently operated stepping switches take up consecutive normally energized positions in the order in which the stepping switches are operated, means for coupling a predetermined number of stepping switches taking up predetermined positions to the car stopping means for their associated floors, the predetermined number of stepping switches operating the car stopping means to which they are coupled, means for returning each of the predetermined number of stepping switches from the predetermined position occupied by the stepping switch to its normal position when a car is stopped at the associated floor whereby each said stepping switch is uncoupled from the associated car stopping means thus rendering inoperative the car stopping means and rendering inoperative the blocking means which de-energized the position prior to said predetermined position, whereby a stepping switch positioned at said prior position moves to said predetermined position.

13. A control for an elevator system serving a plurality of upper floors of a building, comprising car stopping means associated with each said floor and operable to stop a descending car of the elevator system at the associated floor, the car stopping means being rendered inoperative upon stopping a descending car, signalling means for each said floor from which a signal may be made when it is desired to operate the car stopping means associated with that floor, signal registering means responsive to signals made from the signalling means to register the signals in the sequence in which they are made, the signal registering means operating the car stopping means for which signals have been made in the sequence in which the signals are registered, blocking means for delaying the operation of further car stopping means until the number of car stopping means already in operation falls below a predetermined number, means operable automatically to reverse an ascending car at a desired floor of the building, and means for operating said automatic reversing means and including timing means responsive to the time of ascent of the car and means responsive to the number of signals registered.

14. A control for an elevator system serving a plurality of upper floors of a building, comprising car stopping means associated with each said floor and operable to stop a car of the elevator system at the associated floor, the car stopping means being rendered inoperative upon stopping a car, signalling means for each said floor from which a signal may be made when it is desired to operate the car stopping means associated with that floor, signal registering means responsive to signals made from the signalling means to register the signals in the sequence in which they are made, the signal registering means operating the car stopping means for which signals have been

made in the sequence in which the signals are registered, blocking means for delaying the operation of further car stopping means until the number of car stopping means already in operation falls below a predetermined number, a variable timer for controlling the interval between cars of the elevator system, and means responsive to the number of signals registered to vary the timer and thus vary the interval between cars.

15. A control for an elevator system serving a plurality of upper floors of a building, comprising car stopping means associated with each said floor and operable to stop a car of the elevator system at the associated floor, the car stopping means being rendered inoperative upon stopping a car, signalling means for each said floor from which a signal may be made when it is desired to operate the car stopping means associated with that floor, signal registering means responsive to signals made from the signalling means to register the signals in the sequence in which they are made, the signal registering means operating the car stopping means for which signals have been made in the sequence in which the signals are registered, blocking means for delaying the operation of further car stopping means until the number of car stopping means already in operation falls below a predetermined number, a signal light associated with each said floor, means for operating the signal lights when signals are made from the signalling means for their associated floors, and means for flashing selected signal lights.

16. A control for an elevator system serving a plurality of upper floors of a building, comprising signalling means for each said floor from which a signal may be made when it is desired to stop a car of the elevator system at that floor, signal registering means responsive to signals made from the signalling means to register the signals in the sequence in which they are made, and means for stopping a car of the elevator system in response to the longest registered signals on the signal registering means.

17. A control for an elevator system serving a plurality of upper floors of a building, comprising signalling means for each said floor from which a signal may be made when it is desired to stop a car of the elevator system at that floor, signal registering means responsive to signals made from the signalling means to register the signals in the sequence in which they are made, and means for stopping a car of the elevator system in response to the longest registered signals on the signal registering means to answer said longest registered signals, and means for removing the signals from the signal registering means when they have been answered.

18. A control for an elevator system serving a plurality of upper floors of a building, comprising signalling means for each said floor from which a signal may be made when it is desired to stop a car of the elevator system at that floor, signal registering means responsive to signals made from the signalling means to register the signals in the sequence in which they are made, and means for stopping a car of the elevator system in response to the longest registered signals on the signal registering means, a signal light associated with each said floor, means for operating the signal lights when signals are made from the signalling means for their associated floors, and means for flashing the lights that have been in operation the longest.

19. A control for an elevator system serving a plurality of upper floors of a building, comprising signalling means for each said floor from which a signal may be made when it is desired to stop a car of the elevator system at that floor, signal registering means responsive to signals made from the signalling means to register the signals in the sequence in which they are made, and means for stopping a car of the elevator system in response to the longest registered signals on the signal registering means, a signal light associated with each said floor, and means for flashing the signal lights for the floors for which signals have been longest registered.

20. A control for an elevator system serving a plurality of upper floors of a building, comprising signalling means for each said floor from which a signal may be made when it is desired to stop a car of the elevator system at that floor, a signal light associated with each said floor, means for operating the signal lights when signals are made from the signalling means for their associated floors, and means for flashing the lights that have been in operation the longest.

21. A control for an elevator system serving a plurality of upper floors of a building, comprising signalling means for each said floor from which a signal may be made when it is desired to stop

a descending car of the elevator system at that floor, means operable automatically to reverse an ascending car at a desired floor of the building, and means for operating said automatic reversing means and including timing means responsive to the time of ascent of a car and means responsive to the number of signals made from said floors.

22. A control for an elevator system serving a plurality of upper floors of a building, comprising signalling means for each said floor from which a signal may be made when it is desired to stop a car of the elevator system at that floor, a variable timer for controlling the interval between cars of the elevator system, and means responsive to the number of signals made from said floors to vary the timer and thus vary the interval between cars.

HAROLD C. CRANE.
